BOOTH SEAT

Charles L. Hershberger, Joplin, Mo., assignor to H & H Manufacturing Company, Inc., Joplin, Mo., a corporation of Missouri

Filed Apr. 22, 1966, Ser. No. 1,990

Term of patent 14 years

(Cl. D15—11)

FIG. 1 is a perspective view of a booth seat;
FIG. 2 is an end elevational view thereof; and
FIG. 3 is a top plan view of a booth seat.
The back side of the booth seat is plain and unornamented in appearance.

I claim:

The ornamental design for a booth seat, as shown and described.
